UNITED STATES PATENT OFFICE

WILLIAM A. UTTZ, SR., OF FORT WORTH, TEXAS, ASSIGNOR, BY MESNE ASSIGNMENTS,
TO PERFECTION PACKAGE SEALER COMPANY, A CORPORATION OF TEXAS

GUMMED-TAPE-DISPENSING MACHINE

Application filed March 4, 1927. Serial No. 172,712.

This invention relates to gummed tape dispensing machines and has special reference to improvements in the types of gummed tape dispensing machines for which a patent 5 was granted to me on June 13, 1926, Number 1,592,431.

One important object of the invention is to provide an improved arrangement of 10 gummed tape dispensing machine wherein the tape is normally prevented from engaging with the moistener by certain novel arrangements of delivery means.

A second important object of the invention is to provide an improved arrangement of 15 gummed tape dispensing machine wherein tape may be fed forward from the machine to a desired extent without touching the tape with the fingers.

A third important object of the invention 20 is to provide an improved form of tape feeding mechanism so combined with tape cutting mechanism that the same manual means which operates the feeding mechanism by one movement may be caused to actuate the tape severing means by a second movement.

A fourth important object of the invention 25 is to provide a novel and improved arrangement of means whereby the tape will be constantly engaged frictionally by the delivery mechanism.

A fifth important object of the invention is to provide improved means for supporting 30 rolls of tape of different widths.

With the above and other objects in view as 35 will be hereinafter apparent, the invention consists in general of certain novel details of construction and combinations of parts hereinafter fully described, illustrated in the accompanying drawings and specifically 40 claimed.

In the accompanying drawings like characters of reference indicate like parts in the several views, and:

Figure 1 is a side elevation of one preferred form of the tape dispensing machine.

Figure 2 is a plan view thereof.

Figure 3 is a longitudinal section therethrough.

Figure 4 is a section on the line 4—4 of 50 Figure 2.

Figure 5 is a section on the line 5—5 of Figure 2.

Figure 6 is a section on the line 6—6 of Figure 2.

Figure 7 is a section on the line 7—7 of 55 Figure 2.

Figure 8 is a section on the line 8—8 of Figure 2.

Figure 9 is a view of a modified form of the delivery end of the machine in plan. 60

Figure 10 is a perspective view of a certain moistener and tape guide as used herewith.

Figure 11 is a perspective view of a spring plate forming a portion of this guide. 65

Figure 12 is a side elevation of the improved machine in a modified form adapted for support beneath the top of a store counter or shelf.

Figure 13 is an end view of this modified form. 70

Figure 14 is a detail section on the line 14—14 of Figure 13.

Figure 15 is an end view showing a modified means for supporting the machine slidably beneath a counter. 75

Figure 16 is a cross section through a machine of this character showing a modified form of the moistening device for use therewith.

Figure 18 is a perspective view of this modified moistener from the side opposite Figure 16.

Figure 19 is a face view of the web supporting plate of this modified moistener. 85

In the embodiments of the invention here shown there is provided a casing 10 forming a water tank and the rear of this casing is covered by a closure 11 having flanges 12 extending over the sides of the casing 10. Extending longitudinally of this closure the metal is depressed centrally to form a trough like structure 13 wherein may be slid, from the rear end of the machine, a plate 14 having 90 downwardly turned flanges 15 at its sides to hold the body of the plate flush with the surface of the closure 11. Mounted toward the forward end of the closure is a pair of L-shaped brackets 16 and in the upper end of 95 100

these brackets is journaled the shaft 17, the journal ends of this shaft projecting laterally beyond the brackets on each side and preferably being covered with friction rings 18 of rubber or the like. This shaft 17 carries a tape feeding roller 19 which contacts with a plate 20 supported in a well 21 formed in the slide 14. The plate 20 is pressed upwardly toward the roller 19 by suitable springs 22 so that paper or gummed tape passing between the feed roller 19 and the presser plate 20 will be forced frictionally against the roller 19. At the rear end of the machine there is provided a roll support which includes a base plate 23 extending transversely of the machine and provided at each side with downwardly and laterally extending flanges 24 secured to the closure 11 by screws 25 so that the base plate 23 is held in position thereby. At each side of the center of the machine this base plate is provided with a series of spaced slots 26 and supported on the base plate are standards 27 each having a Z-shaped foot 28 so that the respective standard may have its foot engaged in any one of the slots 26 and be held in an upright position. In order to prevent accidental tilting and disengagement of the standards 27 there is provided beneath the base plate 23 a spring presser plate 29 which is urged upwardly by springs 30 surrounding guide pins 31 as shown. The plate 29 engages the under sides of the feet 28 and thus holds the standards 27 from accidental tilting. These standards are provided with slots 32 for the reception of the center pin 33 of a roll 34 of gummed tape. At the end of the slide 14 there is provided an upwardly extending flange 35 which is bent to extend forwardly over the plate 23 as at 36 and is held from movement by pins 37 passing through suitable openings in the lip 36 and base plate 23. By this means the slide is prevented from accidental movement relative to the closure 11.

Extending upwardly from the top of the closure on each side thereof is a series of brackets 38 and to the upper end of each series of brackets there is secured an angle guide bar 39, the brackets being secured to the vertical leg of this guide bar while the horizontal legs project toward each other. Seated in the angles of guide bars 39 are other angle bars 40 which are preferably termed the pull bars. Connecting the bars 40 at the rear end is a tie rod 41 the ends of which project through slots 42 formed in the vertical legs of the members 39. The horizontal leg of each member 39 is provided with a series of stop receiving openings 43 spaced adjacent the edge and these openings are adapted to receive the downwardly extending legs 44 of a stop bar 45 which extends across the machine. The legs 44 extend downwardly far enough to be engaged by the tie rod 41 upon movement of the angles 40 forwardly and by positioning

the stop bar 45 in one pair or the other of the holes 43 the extent of forward movement of the angles 40 may be limited. In order to normally hold these angles 40 in rearward position there is provided at each side of the device a tension spring 46 one end of which is connected to the bar 41 and the rear end of which is secured to a lug 47 formed on the vertical leg of the respective angle 38. The angle bars 40 pass beneath the journal ends of the shafts 17 and are preferably provided on their horizontal legs each with a friction strip 48 engaging the friction band 18. The ends of the bars 40 are connected by a hand grip 49 so that they can be drawn forwardly together. Extending upwardly from the slide 14 are lugs 50 which support a guide bar or roller 51 and the gummed tape is led from the roll 34 along the path 52 beneath this roller 51 and between the feed roller 19 and presser plate 20. The angle bars 40 have an up and down motion at their front and may be lifted to obtain firm engagement between the friction members 48 and 18. When thus engaged and drawn forward by the hand grip 49 the shaft 17, and consequently the feed roller 19 will be rotated and the gummed tape fed forwardly beneath this feed roller. It is to be observed that the rolls of gummed tape in some instances have the gummed side inwardly of each rear end and in other instances outwardly. In the operation of the machine with inwardly gummed tape the tape is fed off the upper part of the roll as shown in Figure 1 but, if the tape be gummed on the outer-side, it will naturally be fed off of the lower part of the roll. Obviously, the amount of tape fed off the roll will be regulated by the position of the stop bar 45 and it will also be obvious that because the feed roll 19 is of larger diameter than the friction bands 18 the amount of tape fed forwardly will be in the same ratio to the forward movement of the angle bars 40, which may be termed for convenience feed bars, as the diameters of the friction band 18 and feed roller 19. Forwardly of the feed roller the sides of the casing 10 are provided with notches 53 wherein is seated a knife frame 54 carrying at each end a pin 55. These pins support a stationary knife blade 56 and on one of these pins, between the blade 56 and frame 54 is pivoted an oscillating knife blade 57 which is normally held slightly raised by means of the spring 58. Pivoted centrally of the knife blade 57 and extending upwardly between guide lugs 58 is an arm 59 having laterally extending fingers 60 which lie beneath the horizontal legs of the feed bars 40. The gummed tape passes between these blades 56 and 57 and upon the feed bars being drawn out the forward end of these bars may be depressed so that the upper blade 57 is swung down

scissors fashion across the blade 56 and the tape severed. Just to the rear of these knife blades there is provided on the slide up-standing lugs 61 which carry a cross bar 62 on which are slidably mounted short sleeves 63 carrying guide fingers 64 having downwardly turned ends 65 which are arranged to pass through selected openings 66 in a guide plate 67 supported in spaced relation to the top of the slide 20, corresponding openings being also made in the slide for these ends. By this arrangement guide means is afforded for the forward end of the tape. In front of the blades there is provided a lower guide plate 68 preferably of 15 spring metal and having an upturned forward end provided with side guide lugs 69. Spaced above this is an upper guide plate 70 which has a forward edge 71 which may be serrated as shown in Figure 9 or may be without serrations as shown in Figure 2. In some instances it is preferred, as shown in the form for use beneath the counter, to use these serrations since no knife is used in this 20 form. In other instances, where a knife is used, the serrations may be omitted.

The moistening device is indicated in general at 72 and may be the same type as shown in my copending application above referred to but it is to be noted that the moistening device is so positioned that normally the extremity of the tape which projects from between the plates 68 and 70 does not contact with the moistening device but may be pressed 35 down thereon as the tape is fed off.

In the modified form of the invention adapted for support beneath a counter or the like the casing is provided with L-shaped hangers 72' which engage in guide bars 73 secured beneath the counter and there may be either two individual guide bars as shown in Figure 14 or there may be a single plate 74 having its edges bent to form channels 75. In this form the paper roll hangs downwardly, this part of the invention being simply inverted. In this form the knife blades are omitted, dependence being had on the serrated forward edge of the upper guide 40 70.

In the modified form of moistening device 50 the body of the device is formed of stamped metal and consists of a body plate 76 having pivot lugs 77 projecting from the sides and also having rearwardly extending weight carrying arms 78 stamped from the sheet metal 55 and bent rearwardly, these arms being provided each with a notch 79 for engagement by the reversely notched end of a weight bar 80. The usual absorbent band 81 extends around the body 76, notches 82 being provided to hold 60 it in position.

In operation the handle 49 is grasped, raised slightly and drawn forward. This produces intimate contact between the parts 48 and 18 and revolves the feed roller 19 which 65 feeds the tape 52 forwardly through the guide

and over the moistener. The moistened strip of tape is then raised and torn off against the front edge of the member 70.

There has thus been provided a simple and efficient device of the kind described and for 70 the purpose specified.

It is obvious that minor changes may be made in the form and construction of the invention without departing from the material spirit thereof. It is not, therefore, desired 75 to confine the invention to the exact form herein shown and described, but it is desired to include all such as properly come within the scope claimed.

Having thus described the invention, what 80 is claimed as new, is:

1. In a machine of the class described, a feed roller for operatively engaging tape to be dispensed, and tiltable feed bars mounted for longitudinal movement and arranged to engage and rotate the roller upon being tilted and moved longitudinally, said feed bars being normally free from the roller until tilted to engaging position.

2. In a machine of the class described, a 90 feed roller for operatively engaging tape to be dispensed, said feed roller having journal end portions, and longitudinally movable feed bars adapted to tilt and engage the journal end portions and rotate said roller, said feed 95 bars being normally free from the roller until tilted to engaging position.

3. In a machine of the class described, a feed roller for operatively engaging tape to be dispensed, said feed roller having end portions, longitudinally movable feed bars adapted to tilt and engage the end portions and rotate said roller, and bearings supporting said ends and holding the roller against movement transverse its axis upon engagement by the feed bars, said feed bars being normally free from the roller until tilted to 100 engaging position.

4. In a machine of the class described, a feed roller for operatively engaging tape to 110 be dispensed, said feed roller having journal end portions, longitudinally movable feed bars adapted to tilt and engage the end portions and rotate said roller, and bearings supporting said ends and holding the roller against movement transverse its axis upon engagement by the feed bars, said bars being 115 depressible to free them from engagement with the roller ends whereby the bars may be moved in one direction without rotating the 120 roller.

5. In a machine of the class described, a feed roller for operatively engaging tape to be dispensed, said feed roller having journal end portions, longitudinally movable feed 125 bars adapted to engage end portions and rotate said roller, bearings supporting said ends and holding the roller against movement transverse its axis upon engagement by the feed bars, said bars being depressible to free 130

them from engagement with the roller ends whereby the bars may be moved in one direction without rotating the roller, and springs for returning said bars to initial position after movement of the roller.

6. In a machine of the class described, a feed roller for operatively engaging tape to be dispensed, said feed roller having journal end portions, longitudinally movable feed bars adapted to engage the end portions and rotate said roller, friction bands on said ends, and friction strips on the portions of the bars engaging the bands.

7. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, friction bands on said ends, and friction strips on the portions of the bars engaging the bands.

8. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller ends whereby the bars may be moved in one direction without rotating the roller, friction bands on said ends, and friction strips on the portions of the bars engaging the bands.

9. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller ends whereby the bars may be moved in one direction without rotating the roller, springs for returning said bars to initial position after movement of the roller, friction bands on said ends, and friction strips on the portions of the bars engaging the bands.

10. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller ends whereby the bars may be moved in one direc-

tion without rotating the roller, a tape severing blade in advance of said roller, and means on said blade engageable by the bars upon depression of their forward ends and arranged to actuate the blade upon depression of the bars.

11. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller ends whereby the bars may be moved in one direction without rotating the roller, springs for returning said bars to initial position after movement of the roller, a tape severing blade in advance of said roller, and means on said blade engageable by the bars upon depression of their forward ends and arranged to actuate the blade upon depression of the bars.

12. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller ends whereby the bars may be moved in one direction without rotating the roller, friction bands on said ends, friction strips on the portions of the bars engaging the bands, a tape severing blade in advance of said roller, and means on said blade engageable by the bars upon depression of their forward ends and arranged to actuate the blade upon depression of the bars.

13. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller ends whereby the bars may be moved in one direction without rotating the roller, springs for returning said bars to initial position after movement of the roller, friction bands on said ends, friction strips on the portions of the bars engaging the bands, a tape severing blade in advance of said roller, and means on said blade engageable by the bars upon depression of their forward ends and arranged to actuate the blade upon depression of the bars.

14. In a machine of the class described, a feed roller for operatively engaging tape to

be dispensed, feed bars mounted for longitudinal movement and arranged to tilt and engage and rotate the roller upon being moved longitudinally, a presser plate beneath said roller, and means normally urging said presser plate toward the roller, said feed bars being normally free from the roller until tilted to engaging position.

15. In a machine of the class described, a feed roller for operatively engaging tape to be dispensed, said feed roller having journal end portions, longitudinally movable feed bars adapted to tilt and engage the end portions and rotate said roller, a presser plate beneath said roller, and means normally urging said presser plate toward the roller, said feed bars being normally free from the roller until tilted to engaging position.

16. In a machine of the class described, a feed roller for operatively engaging tape to be dispensed, said feed roller having journal end portions, longitudinally movable feed bars adapted to tilt and engage the end portions and rotate said roller, bearings supporting said ends and holding the roller against vertical movement upon engagement by the feed bars, a presser plate beneath said roller, and springs normally urging said presser plate toward the roller.

30 17. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller 40 ends whereby the bars may be moved in one direction without rotating the roller, a presser plate beneath said roller, and means normally urging said presser plate toward the roller.

45 18. In a machine of the class described, a feed roller for operatively engaging tape to be dispensed, said feed roller having journal end portions, longitudinally movable feed bars adapted to engage the end portions and rotate said roller, bearings supporting said ends and holding the roller against movement transverse its axis upon engagement by the feed bars, said bars being depressible to free them from engagement with the roller 50 ends whereby the bars may be moved in one direction without rotating the roller, springs for returning said bars to initial position after movement of the roller, a presser plate beneath said roller, and means normally urging said presser plate toward the roller.

55 19. In a machine of the class described, a feed roller for operatively engaging tape to be dispensed, said feed roller having journal end portions, longitudinally movable feed bars adapted to engage the end portions and

rotate said roller, friction bands on said ends, friction strips on the portions of the bars engaging the bands, a presser plate beneath said roller, and means normally urging said presser plate toward the roller.

20. In a machine of the class described, a feed roller for operatively engaging tape to be dispensed, said feed roller having journal end portions, longitudinally movable feed bars adapted to engage the end portions and rotate said roller, bearings supporting said ends and holding the roller against vertical movement upon engagement by the feed bars, said bars being depressible to free them from engagement with the roller ends whereby the bars may be moved in one direction without rotating the roller, a tape severing blade in advance of said roller, means on said blade engageable by the bars upon depression of their forward ends and arranged to actuate the blade upon depression of the bars, laterally adjustable tape roll supports in laterally adjusted position, laterally adjustable tape guides between the roller and blade, and means to hold said guides in adjusted position.

21. In a machine of the class described, a feed roller for operatively engaging tape to be dispensed, said feed roller having journal end portions, longitudinally movable feed bars adapted to engage the end portions and rotate said roller, bearings supporting said ends and holding the roller against vertical movement upon engagement by the feed bars, said bars being depressible to free them from engagement with the roller ends whereby the bars may be moved in one direction without rotating the roller, a tape severing blade in advance of said roller, means on said blade engageable by the bars upon depression of their forward ends and arranged to actuate the blade upon depression of the bars, laterally adjustable tape roll supports in laterally adjusted position, laterally adjustable tape guides between the roller and blade, and means to hold said guides in adjusted position.

In testimony whereof I affix my signature.
WILLIAM A. UTTZ, Sr.
